[57] **CLAIM**

The ornamental design for a combined book mark and line indicator, as shown and described.

DESCRIPTION

FIG. 1 is a rear elevational view of a combined book mark and line indicator showing my new design;

FIG. 2 is a front elevational view;

FIG. 3 is a left side elevational view, the right side being a mirror image thereof;

FIG. 4 is an end elevational view, the opposite end being a mirror image thereof;

FIG. 5 is a front perspective view; and,

FIG. 6 is a rear perspective view.

*FIG. 1**FIG. 3**FIG. 2**FIG. 4**FIG. 5**FIG. 6*
